UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed August 25, 1920. Serial No. 405,820.

To all whom it may concern:

Be it known that I, WINFRED T. POWELL, a citizen of the United States, residing at Rochester, in the county of Monroe and 5 State of New York, have invented certain new and useful Improvements in Automatic Telephone Systems, of which the following is a full, clear, concise, and exact description. This invention relates to telephone systems, 10 and more particularly to telephone systems employing automatic switches in completing telephone connections between calling and called subscribers.

In one type of automatic telephone systems now in use, the automatic switches are adjusted in response to directive impulses caused by the interruption of an impulse circuit including the two sides of the calling subscriber's line in series. In such arrangements it is necessary to distinguish between momentary interruptions of the subscriber's line at the time of the transmission of directive impulses and the long interruption of the subscriber's line at the termination of a call, which long interruption of the line may be referred to as a release impulse.

In systems of the present time an arrangement of fast and slow releasing relays are 30 employed to distinguish between these various kinds of impulses, and while the result is accomplished by the use of these slow relays they must be adjusted to operate on such narrow time limits that they will not 35 operate satisfactorily with substation impulse senders that operate slowly or very rapidly.

The present invention has for its purpose the elimination of the slow operating 40 relays in connection with the setting and release of numerical switches, and replaces them by fast acting relays which are controlled by one or more mechanical timing devices. In such a system it is also contemplated to eliminate the sequence controlling device which is commonly referred to 45 as a side switch.

In the drawings with Fig. 1 placed at the left of Fig. 2, there is diagrammatically 50 represented a portion of a telephone system employing the present invention. At the left of Fig. 1 there is represented a subscriber's substation circuit and line, as well as a line switch individual to this line.

Between the dotted lines of Fig. 1 there is 55 represented a circuit arrangement for relaying or repeating impulses to a distant office known as a repeater. This line switch and repeater are herein represented as located at the same office. At the extreme right of Fig. 1 and the left of Fig. 2 there is 60 represented a selector switch located at a distant office herein referred to as office #2. At the right of the dotted line in Fig. 2 there is 65 represented a connector switch, also located at office #2, and a called line and its substation circuits.

It will be understood that in a large system a first and a second numerical switch or selector of the character shown in Figs. 70 1 and 2 will be interposed between the line switch and repeater at office #1, but the arrangement of these numerical switches forms no part of the present invention. The line switch referred to in this system may 75 be of the structure disclosed in the patent to Clement, #1,107,153, issued Aug. 11, 1914, and the operating circuits of this switch may be of the design in which the 80 brushes of the switch remain in engagement with the trunk terminals last used and may be similar to those shown in the patent to Lamb, #1,193,160, patented Aug. 1, 1916. The structure of the selector switch may be 85 substantially similar to that disclosed in the patent to Keith, et al. #815,321, issued Mar. 13, 1906, and the connector switch is similar to that disclosed in the patent to Keith, et al. #815,176, patented Mar. 13, 1906, when said last named switches have 90 been modified to operate in a two-wire system without side switches.

The relay 50 of the repeater is of the type 95 commonly referred to as electro-polarized. The left hand winding of this relay is inefficient and will not attract the armature of this relay. The right hand winding, however, of this relay is efficiently wound and is so arranged that the current in one direction will oppose the effect of the left hand 100 winding, but with current in the other direction both windings will co-operate to attract the armature of the relay.

In Figs. 1 and 2 there is shown an interrupting or timing device with parts referred 105 to as interrupter #1 and interrupter #2. These two interrupters may be in the form of insulating cams mounted on a constantly

rotating shaft, or may be of any structure in which the contacts 20 and 21 of Fig. 1 are closed for intervals in the sequence and relation indicated by Fig. 1. One of these sets 5 of interrupters or interrupting device will serve for all the circuits located at one office.

It is believed that the invention will best be understood by describing the method of establishing a telephone connection from a 10 substation indicated at A to a called substation indicated at B. When the subscriber at A initiates a call by removing his receiver from its switchhook, the line relay 5 of the line switch, individual to the calling line, is 15 energized to start the operation of the line switch to connect this line to an idle trunk. The energizing circuit for the slow releasing relay 5 extends from grounded battery, winding of this relay, upper back contact 20 and armature of relay 6, through the upper side of the calling line and its substation circuits, through the lower side of the line, inner armature and back contact of the cut-off relay 6 to ground. The line relay 5 is 25 operated in this circuit and at its inner armature and contact places a guarding potential on the test contact of the calling line at the group of connectors at which it terminates, so that this line cannot be 30 seized at this time as a called line. At the outer armature and contact of relay 5 an operating circuit is closed for the motor magnet 8 of the line switch, this circuit extending from grounded battery, winding, back contact and armature of the motor magnet 8, outer armature and contact of line 35 relay 5, lower contact and armature of the cut-off relay 6, test brush 9, of the line switch, test contact 11 to ground over the 40 test conductor of busy trunks.

Let it be assumed that the trunk with which the brushes of the line switch were in operative relation was busy, under which condition a guarding potential exists on the 45 test contact corresponding to 11 of this trunk, being applied from ground, through the left hand armature and front contact of relay 10 and conductor 12. Under the control of the motor magnet and its operating 50 circuits, the line switch advances its test brushes until the test brush 9 engages the test contact 11 of a trunk that is disengaged, a condition which is indicated by the absence of potential on its test contact. As soon as 55 the idle trunk is reached, the cut-off, relay 6 is operated in a circuit from grounded battery, winding, back contact and armature of the motor magnet 8, cut-off relay 6, inner contact and armature of line relay 5 60 to ground. The cut-off relay through its upper armatures and front contacts extends the calling line to the line switch brushes 13 and 14, and through these brushes closes a circuit for the impulse relay 15 of the repeater. The impulse relay 15 is operated in 65

this circuit, and at its armature and front contact closes a circuit through the left hand winding of the primary release relay 16. The primary release relay attracts its armature, and closes a locking circuit for itself 70 while contacts 20 of interrupter #1 are closed, and at its upper contact closes a circuit from ground, through the left hand winding of the secondary release relay 10 to grounded battery. This last named relay 75 attracts its armatures, closing a locking circuit for itself while contacts 21 are closed, and at its left hand armature and front contact extends a holding ground over conductor 12, test contact 11, test brush 9, lower 80 armature and front contact of the cut-off relay, winding of this relay, armature, back contact and winding of the motor magnet 8 to grounded battery.

It will be noted that the cut-off relay on this operation interrupts the operating circuit of the line relay 5, but this last named relay is designed to release its armature slowly so that it maintains the original 85 energizing circuit of the cut-off relay 6 until the holding circuit has been completed at the relay 10 of the repeater. The repeater is now in condition to receive impulses from the substation sender S over the impulse 90 circuit including the impulse relay 15. This impulse is ordinarily closed for an appreciable interval before the subscriber starts sending impulses. The subscriber now 95 operates his sender S to transmit a series of impulses corresponding to the first digit of the wanted number. In response to this series of impulses, the impulse relay 15 vibrates its armatures. At the first retraction of the inner armature of the impulse 100 relay 15, a circuit is closed from ground, outer right hand armature of the secondary 105 release relay 10, left hand winding of the primary change-over relay 18 to grounded battery. The change-over relay attracts its 110 armature and at its upper contact closes a circuit from ground, through the lower winding of the secondary change-over relay 19 to grounded battery. This last named relay attracts its armatures and at its lower 115 armature and front contact closes an impulse circuit for the first selector switch at the distant office, as will be described. At the lower contact and armature of the primary change-over relay 18, a locking circuit 120 is closed through the right hand winding of this relay, contacts 20 of the interrupter #1, to grounded battery, provided these contacts are closed. The purpose of this locking circuit will be hereinafter described. It should be noted that the relation between 125 the sets of contacts of interrupter #1 and interrupter #2, should be such that the release magnets will not be operated in response to the directive impulses which are of short relation, but will permit the opera- 130

tion of these magnets in response to a long interruption of the impulse circuit.

In response to the remaining impulses of this circuit, the impulse relay 15 will retract its armatures, but at this time an impulse repeating circuit is closed for the impulse relay 22 of the selector from grounded battery, right hand winding of this relay, uppermost armature and back contact of the switching relay 23, lower front contact and armature of the secondary change-over relay 19, outer right hand armature and front contact of the impulse relay 15 of the repeater, inner armature and back contact of switching relay 23, left hand winding of the impulse relay 22 to ground.

In response to this first series of impulses, the impulse relay 22 vibrates its armature. At the first closure of the impulse circuit when the impulse relay 22 attracts its armature, a circuit for the primary release relay 24 is closed from grounded battery, left hand winding of this relay, through contact, and armature of the impulse relay 22 to ground. In the event that the contacts 25 of the interrupter #1 at the distant office in which the selector is located are closed, a circuit is completed from grounded battery, through contacts 25, conductor 26, and right hand winding of the primary release relay 24 to ground. Under the control of this circuit the primary release relay is intermittently locked operated for a purpose to be pointed out.

As soon as the upper contact and armature of relay 24 is closed, a circuit is completed through the left hand winding of the secondary release relay 27, and in the event that the contacts 28 of the interrupter #2 are closed, a circuit is completed from grounded battery, through contacts 28, conductor 29, right hand winding of the secondary relay 27, its contact and armature to ground.

It should be noted at this point that the circuit for the release magnet 30 of the selector is controlled at the back contact of the secondary release relay 27, back contact of the switching relay 23, and back contact of the impulse relay 22. During the reception of properly timed impulses from the repeater, the circuit of the release magnet 30 is closed at the back contact of the impulse relay 22, but at this time the secondary release relay 27 will be operated so that the release magnet circuit is not completed. It will be seen that before the release of the selector switch can be effected, the secondary release relay 27 must be deenergized, but this relay is held operated first in a circuit completed at the armature and contact of the primary release relay 24, and also over the locking conductor 29. In order to effect a release, it is necessary for the impulse relay 22 to retract its armature which opens the original operating circuit of the primary re-

lease relay 24. Then in the event that the contacts 25 of interrupter #1 are closed, the primary release relay 24 will be locked operated until the interrupter #1 has rotated to open the contacts 25. Although the original 70 operating circuit of the secondary release relay 27 is open at the contact and armature of relay 24, it will be held locked until the contacts 28 of interrupter #2 have passed through a complete closed cycle. The period 75 during which the contacts 28 of interrupter #2 are closed is of such length that the impulse relay 22 will have attracted its armatures if the interruption of the impulse circuit is due to sending impulses and not due 80 to a long release impulse.

Having thus described how the release of the selector is prevented in response to properly timed impulses in response to a subscriber's substation sender, it will now be described how the selector is operated in response to these directive impulses repeated by the repeater from the substation sender. In response to each impulse, the impulse relay 22 of the selector retracts its armature, and since the secondary release relay 27 is energized during the transmission of properly timed impulses, a circuit is closed for the primary magnet 31 of the selector extending from grounded battery, winding of this magnet, left hand winding of the primary change-over relay 32, outer front contact and armature of relay 27, lower back contact and armature of relay 23, and back contact and armature of the impulse relay 22 to ground. In response to each of these directive impulses relayed from the repeater, the primary motor magnet 31 of the selector switch advances its brushes step-by-step to 95 select a group of trunks through which the wanted subscriber can be reached. The primary change-over relay 32 is operated in series with the primary motor magnet 31 100 and attracts its armatures. At its armature and contact a locking circuit is closed for itself through its right hand winding, conductor 26, contacts 25 of the interrupter #1 to grounded battery in the event that the interrupter is at that time in closed position. 105 With the primary change-over relay 32 operated, a circuit is closed for the secondary change-over relay 34 extending from grounded battery, left hand winding of this relay, and front contact and armature of relay 32 to ground. The secondary change-over relay 34 when operated closes a circuit from ground through its lower contact and armature and right hand winding, conductor 29 and contact 28 to grounded battery in the 110 event that the interrupter #2 is in such position that the contacts 28 are closed. It will be noted at this point that the interrupters #1 and #2 likewise control the change-over 115 from the primary to the secondary operation of the selector switch by measuring an in-

120
125
130

terval of time greater than the interval between the impulses of a series and less than the interval between two series of impulses. In other words, the secondary change-over relay 34 has its circuit closed either at the primary change-over relay 32 or through its locking circuit at the contacts 28 of interrupter #2, as long as impulses are being received by the selector switch but as soon as a time interval greater than that between impulses of series has passed, the locking circuit controlled at contacts 28 will be opened and change-over relay 34 will retract its armature. After the contacts 35 of the off normal switch have been closed after the first primary step of the selector and as soon as the secondary change-over relay is operated, the marginal relay 36 is operated in a circuit closed from grounded battery, its winding, contacts 35 and upper contact and armature of relay 34 to ground. Relay 36 as soon as operated is locked energized in a circuit traceable from grounded battery, winding of this relay, contacts 35, conductor 37, armature and back contact of the secondary motor magnet 38, right hand front contact and armature of relay 36, conductor 39 and inner right hand armature and front contact of relay 27 to ground.

As soon as the secondary change-over relay deenergizes and with relay 36 operated, a circuit is closed for the secondary motor magnet 38, from grounded battery, its winding, left hand contact and armature of relay 36, and back contact and armature of secondary change-over relay 34 to ground. Under the control of this circuit the secondary motor magnet advances the brushes of the selector into engagement with the first trunk of the selected group. In the event that this trunk is engaged, a guarding potential is applied to its test contact 40 from ground at the left hand armature of the secondary release relay 41 of its associated connector switch. When the test brush 42 engages a busy test terminal 40 of an engaged trunk, the relay 36 is operated in a circuit extending from grounded battery, its winding, off normal contacts 35, conductor 37, armature and back contacts of secondary motor magnet 38, conductor 43, inner lower back contact and armature of relay 23, conductor 44, test brush 42 and test terminal 40 to ground. With the relay 36 again energized, the operating circuit of the secondary motor magnet 38 is again closed and this magnet will advance the selector brushes one step. It will thus be seen that during the time that the selector is testing busy trunks, the relay 36 is operated to close a circuit for the secondary motor magnet, and the operation of this motor magnet opens the energizing circuit of the relay 36. This operation continues until the test brush 42 engages an ungrounded test contact at which time a

circuit is closed from grounded battery, winding of relay 36, off normal contacts 35, conductor 37, armature and back contact of secondary motor magnet 38, conductor 43, winding of switching relay 23 and left hand contact and armature of relay 27 to ground. The switching relay 23 is operated in this circuit to extend the selected trunk to the brushes 45 and 46 of its selector switch. The relay 36, however, is marginal and will not operate in series with the relay 23.

As soon as the switching relay 23 of the selector has closed its contacts, a circuit is completed for the impulse relay 48 of the connector switch extending from grounded battery, right hand winding of relay 48, right hand back contact and continuity spring of relay 49, over the upper side of the selected trunk, selector brush 45, uppermost front contact and armature of relay 23, upper back contact and armature of the secondary change-over relay 19, right hand winding of relay 50, winding of the impedance coil 51, lower back contact and armature of relay 19, and outer right hand armature and front contact of relay 15, inner upper armature and front contact of relay 23, selector brush 46, over the lower side of the selected trunk, left hand continuity spring and back contact of relay 49 and left hand winding of the impulse relay 48 to ground. The impulse relay is actuated in this circuit and attracts its armature to close a circuit from ground, its armature and front contact, left hand winding of the primary release relay 52 of the connector to grounded battery. Relay 52 is operated in this circuit and as soon as contacts 25 are closed during the rotation of interrupter #1, relay 52 is locked operated through contacts 25, its right hand winding, and front contact and armature to ground. Also at the upper contact and armature of relay 52, a circuit is closed through the left hand winding of secondary release relay 41 to grounded battery, and this last named relay closes a locking circuit for itself from ground, its armature, front contact and right hand winding to grounded battery as soon as contacts 28 are closed in the operation of interrupter #2. Also at upper contact and armature of relay 41, a circuit is closed from ground, through primary off normal contacts 53, which contacts are opened after the first vertical step of the connector, left hand winding of the change-over relay 54 to grounded battery. The relay 54 is thus caused to attract its armature, and at its innermost armature and front contact closes a locking circuit for itself through its right hand winding whenever the contacts 28 of interrupter #2 are closed. At the middle armature and front contact of this relay a second locking circuit is closed for the

relay 54, through its left hand winding as long as the primary change-over relay 55 has its upper contact and armature closed. At the back contact and middle armature 5 of relay 54, the original energizing circuit of the tertiary change-over relay 95 is held open during the primary operation of the connector switch. At the outermost armature and front contact of relay 54 a break 10 point in the operating circuit of the primary magnet 56 of the connector is closed, and at this back contact and armature, an operating circuit of the secondary motor magnet 57 of the connector is held open.

15 In response to the tens series of impulses repeated by the repeater, impulse relay 48 vibrates its armature and at its front contact intermittently closes a circuit through the left hand winding of the primary release relay 52, and at its back contact closes a stepping circuit for the primary motor magnet 56 of the connector from ground. 20 armature and back contact of the impulse relay, outer armature and front contact of the secondary release relay 41, left hand winding of primary change-over relay 55, outer-most armature and front contact of the secondary change-over relay 54, winding of the primary motor magnet 56 to 25 grounded battery. In response to each of these closures of the operating circuit of the motor magnet, this magnet advances the brushes 58, 59 and 60 of the connector in a primary or group hunting movement 30 until they are directly placed in operative relation to the group of lines in which the wanted line terminates.

It should be noted that the circuit of the release magnet 61 of the connector extends 40 from grounded battery through the winding of this magnet, primary off normal contact 62, outer back contact and armature of secondary release relay 41, back contact and armature of impulse relay 48 to ground. During 45 the transmission of impulses to the impulse relay, this relay closes its back contact, but the release circuit is held open at the back contact and armature of relay 41, and it will be seen that the secondary release relay 41 is held operated during the interval 50 that properly timed impulses from the substation sender are being relayed to the impulse relay, but as soon as a release impulse 55 is conveyed to the connector switch, the impulse relay will be de-energized for a longer interval than that caused by the receipt of a directive impulse, and the secondary release relay 41 de-energizes. As was pointed out in connection with the selector circuit, 60 the rotating interrupters #1 and #2 are so arranged that after the primary release relay 52 is once operated, it is locked in this condition through the contacts 25 for a certain interval the length of time depending upon the position of interrupter 65

#1 when the relay 52 is operated. The operation of relay 52 causes the operation of the secondary release relay 41, and when once operated this relay is locked in this condition during the time that the contacts 70 28 are closed at interrupter #2, and this closure of contacts 28 is maintained for an interval greater than that occupied by a directive impulse, and less than that of a release impulse. It will be seen that the 75 connector will not be released during the impulse circuit interruptions employed in setting the connector switch.

After the transmission of the tens series 80 of impulses a slight period of time intervenes before the last series of impulses are sent from the substation impulse sender. During this period the impulse relay 48 holds its armature attracted and thereby 85 interrupts the original energizing circuit of the primary change over relay 55, and as soon as interrupter #1 has rotated to open its contacts 25, the locking circuit is broken for the relay 55 causing it to de-energize. The de-energization of relay 55 opens the 90 locking circuit including the left hand winding of relay 54 and its middle armature and front contact, and when contacts 28 of the interrupter #2 are open the locking circuit including the right hand winding 95 of relay 54 is broken, and this relay retracts its armatures. The calling subscriber thereupon operates his substation sender to transmit impulses corresponding to the last digit of the wanted number of 100 the subscriber's line, and this last series of impulses is repeated by the repeater to the impulse relay 48 of the connector switch. In response to this last named series of 105 impulses the relay 48 vibrates its armature, at its front contact preventing the release of the connector switch, and at its back contact closing a circuit from ground through the outer armature and front contact of relay 41, left hand winding of the primary 110 change-over relay 55, outer-most armature and back contact of secondary change-over relay 54, outer armature and back contact of test relay 63, conductor 64, lower-most armature and back contact of the cut-through relay 65, winding of the secondary motor magnet 57 to grounded battery. In response to the first retraction of the armature of the impulse relay 48, the secondary 115 motor magnet 57 and the primary change-over relay 55 are energized in series; the secondary motor magnet to advance the connector brushes one step, and the change-over relay 55 to close a circuit from ground, its armature and upper contact, armature and back contact of relay 54, right hand winding of the tertiary change-over relay 95 to grounded battery. This last named relay when actuated closes a locking circuit 120 for itself from ground through its armature and back contact of relay 54, right hand winding of the tertiary change-over relay 95 to grounded battery. This last named relay when actuated closes a locking circuit 125 for itself from ground through its armature and back contact of relay 54, right hand winding of the tertiary change-over relay 95 to grounded battery. This last named relay when actuated closes a locking circuit 130 for itself from ground through its armature and back contact of relay 54, right hand winding of the tertiary change-over relay 95 to grounded battery.

ture, front contact and left hand winding to grounded battery whenever contacts 28 are closed. Also as soon as relay 95 is actuated, a substitute circuit for the secondary motor magnet 57 is closed from grounded battery, its winding, lowermost contact and armature of relay 65, front contact and right hand armature of relay 95, outermost back contact and armature of relay 54, left hand winding of relay 55, outermost front contact and armature of relay 41, and back contact and armature of impulse relay 48 to ground. The purpose of the first described operating circuit for the motor magnet over conductor 64 is to operate the motor magnet before the relay 95 is actuated, which does not take place until the first secondary impulse. Thereafter it is desired to control the secondary motor magnet 57 independently of the test relay 63, since at the time when the test brush 60 is engaging the test contacts of busy lines, the test relay 63 is momentarily operated and thereby opens the original operating circuit of this magnet.

The tens and units series of impulses transmitted to the connector switch have been effective in the manner just described to place the connector brushes 58, 59 and 60 in engagement with the multiple terminals 66, 67 and 68 of the wanted line. At the close of the last series of impulses the circuit of the left hand winding of the primary change-over relay 55 is open, and as soon as the locking circuit including the right hand winding of this relay is opened at the contacts 25 of interrupter #1, this relay retracts its armature and opens the energizing circuit including the right hand winding of the tertiary change-over relay 95. After this has taken place, the locking circuit including the left hand winding of relay 95 is opened at the contacts 28 of the interrupter #2. During the period before the tertiary change-over relay de-energizes and while the test brush 60 is engaging test terminal 68 of the wanted line, the test of this line is effected.

Let it be assumed that the wanted line is idle. Under this condition a circuit is closed from grounded battery, through the resistance 69, which may be the cut-off relay of the wanted line, test terminal 68, test brush 60, outer armature and back contact of relay 95, upper winding of the cut-through relay 65, inner armature and back contact of test relay 63, left hand front contact and armature of relay 41 to ground. Relay 65 is operated in this circuit and at its lowermost armature and back contact opens the controlling circuit of the secondary motor magnet 57. At its contact 70 and armature, it applies a guarding potential on the test terminal of the wanted line to prevent its seizure by some other connector

switch, while at its contact 71 and armature it opens the test circuit of relay 63, and at its innermost armature and front contact closes a locking circuit for itself over conductor 72 to ground at the upper contact 70 and armature of relay 41. At the upper armatures and contacts of relay 65, a signaling circuit is closed from the interrupted source of signaling current indicated at Gen. inner back contact and armature of the slow operating trip relay 73, innermost upper armature and contact of relay 65, brush 59, line terminal 67, through the line circuits and bell at the wanted station B, line terminal 66, connector brush 58, uppermost contact and armature of relay 65, uppermost armature and back contact of the trip relay 73, upper winding of this relay to grounded battery. The source of ringing current is thus intermittently applied to the called line to actuate the call signal or bell at the station B. The trip relay 73 is so designed that it will not operate until the called party at substation B responds by removing his receiver from its switchhook, whereupon it is operated to disconnect the source of signaling current and to extend the talking circuit through its upper armatures and front contacts. A locking circuit closed through the lower winding, front contact and armature of trip relay 73, over conductor 72 holds this relay operated to maintain the continuity of the talking circuit and to prevent the reapplication of signaling current to the called line.

As soon as the trip relay has closed its upper armatures and front contacts, a circuit is closed for the called line talking battery, from battery right hand winding of relay 49 over the upper side of the trunk and called line in series, lower side of the trunk, left hand winding of relay 49, lower front contact and armature of relay 73, conductor 72, contact and armature of relay 41 to ground. Relay 49 is operated in this circuit and at its continuity springs and contacts reverses the direction of the battery in the circuit through the left winding of the impulse relay 48, through the selector brush 45, upper-most front contact and armature of relay 23, right hand winding of relay 50, winding of impedance coil, lower back contact and armature of relay 19, right hand armature and front contact of impulse relay 15 of the repeater, inner upper armature and front contact of relay 23, brush 46, and right hand winding of relay 48.

The current in the circuit just described is in such direction that the right hand winding of the electro-polarized relay 50 adds its energizing effect to that of the inefficient left hand winding of relay 50; whereupon the relay 50 attracts its armature and closes a circuit for operating the relay 75. This last named relay through its continuity springs

and contacts reverses the direction of the talking battery fed to the calling party through the windings of relay 15.

Let it be assumed that the wanted station

- 5 B was engaged at the time when the connector brushes 58, 59 and 60 were placed on its line terminals 66, 67 and 68. It will be recalled that the tertiary change-over relay 95 is held operated for a short interval after 10 these brushes have been placed on the wanted line terminals, so that if the wanted line is busy a circuit is closed from grounded battery, winding of the test relay 63, contact 71 and armature of relay 65, continuity 15 spring and armature of relay 95, test brush 60, test terminal 68 and through a multiple terminal and test brush corresponding to 60 of the connector which has previously seized the wanted line, to ground over an armature 20 and contact of that connector similar to the armature of relay 65 and contact 70. As soon as the test relay 63 is operated, it closes a locking circuit for itself from grounded battery, its winding, contact 71 and armature 25 of relay 65, continuity spring of relay 95 which is de-energized, contacts 76, conductor 77, inner front contact and armature of test relay 63, left hand front contact and armature of relay 41 to ground. The 30 test relay will therefore be locked operated until the call is abandoned, and this prevents the cut-through relay 65 from extending the talking circuit to the brushes 58 and 59 which are in engagement with the 35 terminals of the wanted line. Also as long as test relay 63 is operated a busy tone is transmitted to the called line from the source of busy current indicated at Busy, left hand armature and front contact of relay 63, over the circuit which has been extended from the calling line.

When the calling party abandons the call because the called line is busy or terminates the call at the close of conversation, the release of the connection is effected in the following manner: The calling subscriber replaces his receiver on its switchhook, thereby interrupting the circuit of the impulse relay 15, through which battery has been fed to the calling line. The impulse relay retracts its armatures and at its front contact and inner armature opens the original energizing winding of the primary release relay 16. If the release takes place at the time when contacts 20 of interrupter #1 are closed, primary release relay 16 will be held operated over the circuit previously described until these contacts are open. As soon as the relay 16 retracts its armatures 55 it opens the original energizing circuit of the secondary release relay 10 of the repeater, and thereafter the contacts 21 of interrupter #2 are opened following their closure. After a complete closed period 60 after relay 16 retracts its armature, the

secondary release relay 10 retracts its armatures, whereby the circuit through the left hand winding of relay 50 is opened permitting relay 75 to retract its armatures. At the left hand armature and front contact 70 of relay 10 the holding conductor 12 which has maintained the cut-off relay 6 operated, is opened and this relay de-energizes to effect the release of the line switch.

At the outer right hand armature and front contact of the impulse relay 15 of the repeater the impulse circuit of the impulse relay 48 of the connector is opened permitting this relay to retract its armatures. The primary release relay 52 and the secondary release relay 41 co-operating with the interrupters #1 and 2 measure off an interval of time greater than that necessary for the transmission of a directive impulse to the connector switch. After this interval 80 of time has elapsed, the secondary release relay 41 will retract its armatures and will close a circuit for the release magnet 61 of the connector switch from grounded battery, winding of this magnet, primary off 85 normal contact 62, outer back contact and armature of relay 41, and back contact and armature of the impulse relay to ground. Under the control of this circuit the release magnet 61 is operated until the connector is 90 restored to normal, whereupon the primary off normal contacts 62 are opened. At the inner right hand armature and contact of relay 41, the locking circuit for the trip relay 73 extending from conductor 72 is 95 opened and causes this relay to release. The locking circuit for the cut-through relay 65 which also extends over conductor 72, and the lower winding of this relay is also 100 simultaneously opened. In the event that the connector switch has tested a busy line 105 and the test relay 63 therefore locked operated, this previously described locking circuit is interrupted at the left hand front contact and armature of the secondary release relay 41. This same contact and armature of relay 41 also removes the ground from the test contact 40 of the trunk leading to the connector used, and opens the holding circuit previously described as extending through conductor 44, innermost 110 lower armature and front contact of switching relay 23, conductor 43, back contact and armature of secondary motor magnet 38 of the selector, conductor 37, off normal contact 35, winding of relay 36 to grounded battery.

When the last described circuit is interrupted, the switching relay 23 retracts its armatures and closes a circuit for the release magnet 30 of the selector switch, which circuit extends from grounded battery, winding of this magnet, off normal contacts 125 80, back contact and outermost armature of secondary release relay 27, lowermost con-

tact and armature of relay 23, and back contact and armature of the impulse relay 22 of the selector switch to ground. Under the control of this circuit the release magnet 5 30 restores the selector switch to normal position.

What I claim is:

1. In a telephone system, an incoming line, a plurality of outgoing lines, a switch 10 for interconnecting said incoming line with any of said outgoing lines, an impulse relay connectable to said incoming line and responsive to impulses transmitted over the two sides thereof, a set of contacts for said 15 impulse relay, a second relay operating in substantially the same time interval as said impulse relay, means responsive to said impulse relay for directly operating said automatic switch in selecting a desired outgoing line, a set of contacts for said second 20 relay, a release magnet for said switch and a circuit therefor extending through contacts of said relays, and a mechanical device for controlling the operating circuit of 25 said second relay.

2. In a telephone system, an incoming line, a plurality of outgoing lines, a switch for interconnecting said incoming line with any of said outgoing lines, an impulse relay 30 connectable to said incoming line and responsive to impulses transmitted over the two sides thereof, a set of contacts for said impulse relay, a second relay operating in substantially the same time interval as said 35 impulse relay, said second relay having sets of contacts, means responsive to said impulse relay for directly operating said automatic switch in selecting a desired outgoing line, a release magnet for said switch 40 and a circuit therefor extending through contacts of said relays, and a rotating device for controlling the operating circuit of said second relay.

3. In a telephone system, an incoming line, a plurality of outgoing lines, a switch 45 for interconnecting said incoming line with any of said outgoing lines, an impulse relay connectable to said incoming line and responsive to impulses transmitted over the 50 two sides thereof, a second relay operating in substantially the same time interval as said impulse relay, means responsive to said impulse relay for directly operating said automatic switch in selecting a desired outgoing line, a release magnet for said switch 55 and a circuit therefor having two break points controlled at the contacts of said relays, and a unidirectional rotary timing device for controlling the operating circuit of 60 said second relay.

4. In a telephone system, an incoming line, a plurality of outgoing lines, a switch 65 for interconnecting said incoming line with any of said outgoing lines, an impulse relay responsive to impulses transmitted from a

distant point over the two sides of the incoming line in series, a second relay operating in substantially the same time interval as said impulse relay, sets of contacts for said impulse relay and for said second relay, 70 a motor magnet for operating said automatic switch, a circuit therefor extending through normally closed contacts at said impulse relay and normally open contacts at said second relay, said normally closed contacts being intermittently closed in response to impulses, and said normally opened contacts being closed during a series of impulses, a mechanical timing device, and a circuit for said second relay closed at said device. 75

5. In a telephone system, an incoming line, a plurality of outgoing lines, a switch for interconnecting said incoming line with any of said outgoing lines, an impulse relay responsive to impulses transmitted over said incoming line, operating means for said switch controlled at said impulse relay, a release mechanism and off normal contacts for said switch, a release relay controlling said release mechanism, a release circuit for said release mechanism extending through contacts of said release relay and said impulse relay and said off-normal contacts, a rotary timing device and a circuit for said release relay extending through said timing 95 device.

6. In a telephone system, an incoming line, a plurality of outgoing lines, an automatic switch for interconnecting said incoming line with any of said outgoing lines, an impulse relay responsive to impulses transmitted over said incoming line, primary and secondary operating means for said switch responsive to the operation of said impulse relay, a release relay, sequence controlling mechanism for determining the operation of said primary and said secondary operating means, a third relay controlling said mechanism, and a circuit for said relay closed at front contacts of said release relay and back contacts of said impulse relay, a release magnet and off normal contacts for said switch, a circuit for said magnet extending through said off normal contacts and back contacts of said release and impulse relays, and a timing device through which circuits for said third relay and said release relay are completed. 100

7. In a telephone system, an incoming line, a plurality of outgoing lines, an automatic switch for interconnecting said incoming line with any of said outgoing lines, primary and secondary operating magnets for advancing said switch, an impulse controlling device responsive to impulses transmitted over said incoming line for directly operating the primary and secondary operating magnets, a test relay for testing the busy or idle condition of a selected line, a plurality of relays for sequentially con- 115 120 125 130

- 5 trolling the circuits of said primary and said secondary magnets and said test relay, and a rotary timing device associated with said automatic switch co-operating with 70
5 said impulse relay to control said plurality of relays.
8. In a telephone system, an incoming line, a plurality of outgoing lines, an automatic switch for interconnecting said incoming line with any of said outgoing lines, primary and secondary operating magnets for advancing said switch, an impulse relay responsive to impulses transmitted over said incoming line for directly operating 75
10 the primary and secondary operating magnets, a test relay for testing the busy or idle condition of a selected line, a plurality of relays for sequentially controlling the circuits of said primary and said secondary magnets and said test relay, and a rotary timing device associated with said automatic switch co-operating with said impulse relay to control said plurality of relays. 80
- 25 9. In a telephone system, an incoming line, a plurality of outgoing lines, an automatic switch for interconnecting said incoming line with any of said outgoing lines, an impulse relay responsive to impulses transmitted over said incoming line, a primary magnet for said switch, a sequence relay, release mechanism for said switch, a release relay for controlling the operation 90
30 of said release mechanism, a circuit for said primary magnet including said sequence relay and completed at the front contacts of said release relay and back contacts of said impulse relay, and a rotary mechanical device associated with said automatic switch 95
35 for controlling the operation of said impulse relay.
- 40 10. In a telephone system, an incoming line, a plurality of outgoing trunks, an automatic switch for interconnecting said incoming line with any of said outgoing trunks, an impulse relay responsive to impulses transmitted over said incoming line, primary and secondary operating means for said automatic switch, said primary operating means being responsive to said impulse relay, said secondary operating means being controlled over busy outgoing trunks to advance said switch to seize an idle outgoing trunk, a sequence controlling relay, 100
45 a sequence controlling mechanism governed thereby for preventing the operation of the secondary operating means, a circuit for the primary operating means serially including a winding of said sequence controlling relay and controlled at said impulse relay, a rotary timing device associated with said automatic switch and a circuit including 105
50 a second winding of said sequence controlling relay completed at said device.
- 55 11. In a telephone system, an incoming line, contacts in said incoming line, a plurality of outgoing lines, an automatic switch for interconnecting said incoming line with any of said outgoing lines, an impulse relay controlled over said incoming line, 70
60 means for operating said automatic switch controlled by said impulse relay, a second relay for operating the contacts in said incoming line, a release mechanism and off normal contacts for said switch, a release relay for controlling said release mechanism, a rotary timing device associated with said automatic switch for controlling said release relay, and a circuit for said release mechanism controlled at said off normal contacts and at normally closed contacts of said release relay, said second relay and said impulse relay. 80
- 65 12. In a telephone system, an incoming line, a plurality of outgoing lines, a switch for interconnecting said incoming line with any of said outgoing lines, primary and secondary operating means for said switch, a sequence controlling device including a group of relays for determining the primary and secondary operation of said switch, a release magnet for said switch, and means including a group of relays for controlling the operation of said release magnet, and a unidirectional rotary timing device at said 90
70 automatic switch and circuits for said groups of relays completed at said timing device. 95
- 75 13. In a step-by-step mechanism, in combination with a movable element, means for operating said movable element, a motor magnet for actuating said means and a locking device, of a release magnet for disengaging said locking device, a circuit for the motor magnet having normally opened contacts and a circuit for the release magnet having normally closed contacts, a relay for closing the motor magnet circuit and opening that of the release magnet, a normally open circuit for said relay, a rotary timing device, a locking circuit for said relay closed at said rotary timing device, and a source of current supply for said circuits. 100
80
- 85 14. In a step-by-step mechanism, the combination with a movable element, means for operating said movable element, a motor magnet for actuating said means, and a locking device, of a magnet for releasing said locking device, circuits for the motor and release magnets, the former having 105
90 normally open contacts, and the latter normally closed contacts, a mechanical timing device associated with said movable element, a relay for reversing the position of said contacts, a normally open circuit for the relay, means for closing and opening said circuit, and a locking circuit for said relay closed on the actuation thereof at said 110
95 mechanical timing device, a source of current supply for said circuits, and means 120
100
- 105 11. In a telephone system, an incoming line, contacts in said incoming line, a plurality of outgoing lines, an automatic switch for interconnecting said incoming line with any of said outgoing lines, an impulse relay controlled over said incoming line, 70
110 means for operating said automatic switch controlled by said impulse relay, a second relay for operating the contacts in said incoming line, a release mechanism and off normal contacts for said switch, a release relay for controlling said release mechanism, a rotary timing device associated with said automatic switch for controlling said release relay, and a circuit for said release mechanism controlled at said off normal contacts and at normally closed contacts of said release relay, said second relay and said impulse relay. 80
- 115 12. In a telephone system, an incoming line, a plurality of outgoing lines, a switch for interconnecting said incoming line with any of said outgoing lines, primary and secondary operating means for said switch, a sequence controlling device including a group of relays for determining the primary and secondary operation of said switch, a release magnet for said switch, and means including a group of relays for controlling the operation of said release magnet, and a unidirectional rotary timing device at said 90
120 automatic switch and circuits for said groups of relays completed at said timing device. 95
- 125 13. In a step-by-step mechanism, in combination with a movable element, means for operating said movable element, a motor magnet for actuating said means and a locking device, of a magnet for releasing said locking device, circuits for the motor and release magnets, the former having 105
130 normally open contacts, and the latter normally closed contacts, a mechanical timing device associated with said movable element, a relay for reversing the position of said contacts, a normally open circuit for the relay, means for closing and opening said circuit, and a locking circuit for said relay closed on the actuation thereof at said mechanical timing device, a source of current supply for said circuits, and means 130

for interrupting the current in the release magnet circuit.

15. In a telephone system, a selector switch, a release magnet, a release relay, an impulse relay, an energizing circuit for said release magnet and a switch shaft, said energizing circuit adapted to be closed whenever the switch shaft is off normal and the impulse and release relays are deenergized, a 10 mechanical timing device and a plurality of circuits for said release relay, one of which is closed at said mechanical timing device, and means for maintaining one or another of said circuits of the release relay 15 completed during the operation of the impulse relay.

16. A telephone system comprising an automatic switch, an impulse relay, means 20 for energizing said relay upon connection made with said switch, a release relay, a mechanical timing device and circuits for the release relay controlled by said impulse relay and by said mechanical timing device, contact controlling means governed by said release relay during the connection and adjustment of said automatic switch, and a release circuit for said switch controlled by said impulse relay and by said contact controlling means.

30. 17. A telephone exchange system, comprising a two conductor circuit, associated automatic switch mechanism having waiting contacts divided into groups, and a co-operating movable contact, means outside of 35 said switch for rendering some of said waiting contacts busy, means for advancing said moving contact to a desired group of waiting contacts in response to variations of current transmitted over said circuit, means 40 for starting said moving contact in search of an idle contact in that group in response to another current variation transmitted over said circuit, means for continuing the movement of said moving contact in said 45 search, and stopping it only when an idle contact is reached, releasing mechanism for said moving contact, and a unidirectional rotary timing device controlling said release mechanism.

50. 18. In a telephone system, a subscriber's line, substation apparatus on said line including a receiver, a transmitter, and switchhook contacts normally closed by said receiver, an impulse sender included in said line, a plurality of trunks, each terminating 55 in a selector switch, means for automatically connecting said subscriber's line with an idle trunk and its selector switch, trunks terminating in groups at said selector switches, 60 means controlled by said impulse sender for directly operating said selector switch to select a desired group of outgoing trunks, means for thereafter causing said selector switch to automatically hunt for and seize 65 an idle trunk in the selected group, release

mechanism for said selector switch, a connector switch individual to the selected trunk, means for directly operating said connector in group and line selecting movements to select an idle wanted line, an impulse relay, an impulse circuit serially extending through both sides of the selected trunks and subscriber's line and arranged to transmit impulses from said impulse sender to said impulse relay, release mechanism 70 for said connector switch, and a mechanical timing device common to said selector and connector for controlling said release mechanisms.

19. In a telephone system, a calling line 80 and a called line to be switched into connection, a non-numerical switch and a plurality of independently adjustable numerical switches for inclusion in the connection, each of said numerical switches having an individual adjusting magnet, a common relay for transmitting currents to said magnets in succession, restoring mechanism for said non-numerical switch, means associated with said relay and controlled thereby to govern the 90 operation of said restoring mechanism, and means including a mechanical timing device for disabling said restoring means during the actuation of said relay.

20. In a telephone system, a calling line and a called line, means including non-numerical and numerical switches for inter-connecting said lines, a repeater interposed between certain of said switches, said repeater including an impulse relay, an impulse circuit over 100 which said numerical switches are controlled, by said impulse relay, means including a relay for preparing said impulse circuit, restoring mechanism for said switches, means including a release relay in said repeater for 105 controlling the restoration of switches at one side of the repeater, and a mechanical timing device for controlling said release relay and the relay for preparing the impulse circuit.

21. In a telephone system, an incoming 110 line, a plurality of outgoing lines, an automatic switch for interconnecting said incoming line with any of said outgoing lines, an impulse sender associated with said incoming line, means responsive to the operation of 115 said impulse sender for advancing said switch through group and line selecting movements, controlling means for causing the operations of said automatic switch to occur in proper sequence, releasing means for 120 said switch, and a mechanical interrupting device operating throughout the period of time that said switch is in use for causing the operation of said controlling means at the proper time and for preventing the 125 operation of the releasing mechanism during the directive operation of said automatic switch.

22. In a step-by-step mechanism, the combination with a movable element, operating 130

through primary and secondary movements, a primary motor magnet for effecting the primary movement and a secondary magnet for effecting the secondary movement of 5 said movable element, of circuits for said magnets closed in succession, each of said circuits having normally closed and normally open sets of contacts, a relay for controlling the set of closed contracts, an operating 10 circuit leading to the controlling relay and means for sending impulses of current thereover, an electromagnetic device controlling the set of normally open contacts, a timing device common to a plurality of 15 said movable elements and a circuit for said electromagnetic device, means governed by said controlling relay and said timing device for operating said electromagnetic device, and a source of current supply for 20 said circuits.

23. In a step-by-step mechanism, the combination with a movable element, primary and secondary motor magnets for advancing said element successively through its primary and secondary movements, a circuit controlling device provided with an operating magnet for determining the sequence of operation of said primary and secondary motor magnets, other movable elements, a 25 timing device common to a plurality of said elements, a relay co-operating in the control of said operating magnet, circuits for said primary and secondary motor magnets, each of which serially includes said relay and 30 means co-operating with said timing device and relay for controlling the operation of said primary and secondary motor magnets and the magnet of said circuit controlling device.

40 24. In combination with a normally open operating circuit, an impulse transmitter arranged therein, a progressively movable switching mechanism comprising a normally inoperative motor magnet and an electromagnetic device which is adapted to control the operation of the motor magnet in synchronism with current impulses from said transmitter, means actuated upon the closing 45 of the operating circuit for rendering the motor magnet operative, said means being adapted to retain said magnet in operative condition only during the transmission of successive current impulses of given frequency over said circuit, other similar 50 switching mechanisms and a mechanical timing device common to a plurality of said switching mechanisms and cooperating in the control of said last mentioned means.

55 25. In a telephone system, an incoming line, a plurality of outgoing lines, a switch for interconnecting said incoming line with any of said outgoing lines, an impulse relay operated over said incoming line and functioning to control the operation of said

automatic switch, a sequence controlling device for controlling the sequence of operations of said automatic switch, releasing mechanism for releasing said switch, a plurality of relays for controlling said device and said releasing mechanism, said relays 65 being provided with two windings, one winding of each of said relays being responsive to the operation of said impulse relay and the other winding of each of these relays being controlled through self-locking circuits, each self-locking circuit being controlled by one of said last mentioned relays.

70 26. In a telephone exchange system, comprising a control circuit, associated automatic switch mechanisms each having waiting contacts divided into groups and a co-operating moving contact, a primary magnet and associated means for stepping said moving contact to a desired group of waiting contacts, a secondary magnet and associated means for stepping said moving contact to a desired contact in that group, primary and secondary electromagnets for controlling said magnets, means for energizing and deenergizing said electromagnets by closing and opening said control circuit to operate said primary and secondary magnets to bring about the desired movements 75 of said moving contact, and means including a time measuring device common to a plurality of automatic switch mechanisms for determining the period of operation of one of said magnets.

80 27. In a telephone exchange system, a line circuit and automatic switches for connecting the same with called circuits, a relay responsive to all changes in the line circuit and having front and back contacts, a time measuring device common to a plurality of automatic switches, a pair of relays connected to said contacts respectively and being jointly controlled by said line relay and the time measuring device, and operating circuits for one of said switches jointly controlled by 85 said relays.

90 28. In a telephone exchange system, a plurality of metallic line circuits and means for interconnecting them, comprising a number of automatic selective switches and link circuits, a time measuring mechanism common to a plurality of link circuits, electromagnetic actuating and controlling means associated with each link circuit, certain of said electromagnetic means being in part controlled by and being normally extended to said common time measuring mechanism, and means associated with a line when calling to produce groups of current changes 95 therein, each group composed of changes of different durations whereby the actuating and controlling electromagnets in the link circuits may be effectively energized.

100

105

110

115

120

125

29. In a telephone exchange system, a group of lines, switches, a time measuring mechanism common to a plurality of said switches, conductors normally extending from said switches to said time measuring device, multiple terminals of said lines at said switches, multiple test contacts of said lines at said switches, a pair of talking conductors respectively terminating in brushes at said switches, circuit controlling means at each switch controlled in part by said time measuring mechanism, means for moving said switches over the terminals of the lines of said group, and an electromagnetic means at each switch for association with said test contacts and operating the circuit controlling means to maintain open the talking conductors terminating in a switch which is in engagement with the contacts of a line held by another switch.

30. In a step-by-step mechanism, the combination with a movable element, a motor magnet and means operated thereby for advancing said element progressively, of a circuit for said magnet having normally closed and normally opened sets of contacts, a relay for controlling the set of closed contacts, an operating circuit leading to said controlling relay and means for sending impulses of current thereover, electromagnetic means controlling the set of normally opened contacts, a circuit for said electromagnetic means, other movable elements, a time measuring device common to a plurality of said movable elements and arranged to be operated when any of said movable elements are in use, means governed by said time measuring device and said relay for operating said electromagnetic means, and a source of current supply for said circuits.

31. In a step-by-step mechanism, the combination with a movable element, a motor magnet and means operated thereby for advancing said element progressively, of a circuit for said magnet having normally closed and normally opened sets of contacts, a relay controlling the closed contacts and electromagnetic means controlling the open contacts, an operating circuit for said relay and means for sending impulses of current thereover to alternately open and close the contacts controlled thereby, other movable elements, a time measuring mechanism common to a plurality of said movable elements, and a circuit for said electromagnetic means controlled in part by said time measuring mechanism, said last mentioned circuit functioning to maintain the contacts controlled by said electromagnetic means in closed po-

sition during the energizing and deenergizing of said relay.

32. In an automatic telephone system, a progressively movable switching mechanism comprising a normally inoperative motor magnet, a circuit therefor and two electromagnetic devices which control said circuit, the first of said devices acting to place the circuit in condition to receive current impulses and the second device acting to supply current impulses to said circuits, in combination with a metallic telephone circuit and means for dispatching current impulses thereover to operate said devices, other switching mechanisms, and a continuously operating time measuring mechanism common to a plurality of switching mechanisms for continuing the operation of said first device during the transmission of a series of impulses over said metallic circuit.

33. In an automatic telephone system, a progressively movable switching mechanism comprising a motor device which is normally inoperative and means at said switch embodying two parts which operate conjointly by current impulses to render the motor device operative, the first of said parts being adapted to cause a continued actuation thereof in response to said impulses, other switching mechanisms, a time measuring mechanism common to a plurality of said switching mechanisms and cooperating in the control of said first part, in combination with a telephone instrument circuit, and means for transmitting impulses thereover to jointly control said operating parts.

34. In an automatic telephone system, a progressively movable switching mechanism comprising a normally inoperative motor device and means embodying two parts which operate conjointly by current impulses to render the motor device operative, the first of said parts being adapted to be operated to cause a continued actuation of the motor device, the other part being adapted to operate independently to subsequently render the motor device inoperative upon the cessation of its actuation, and a time measuring mechanism common to a plurality of switching mechanisms for determining the period of operation of said other part, in combination with a telephone instrument metallic circuit, and means for transmitting current impulses thereover to control the conjointly operating parts.

In witness whereof, I hereunto subscribe my name this 23rd day of August A. D., 1920.

WINFRED T. POWELL.
